SMOKE SIGNALING DEVICE

Joseph W. Van Karner, New York, N. Y.

Application November 14, 1944, Serial No. 563,417

5 Claims. (Cl. 102—37.4)

1

This invention relates to a smoke signaling device.

In my copending application, Serial No. 513,798, filed December 10, 1943, which became Patent Number 2,423,859 on July 15, 1947, I have disclosed and claimed a device for producing smoke to be used as a distress signal particularly by those lost at sea. The device of that application is adapted to be tossed into the sea promptly after being ignited and to emit a column of smoke while floating on the water. The device of that application has been found to be very effective in actual use and to fulfill its intended purpose. However, it is relatively large and expensive.

The object of the present invention is to provide a somewhat smaller, more compact and less expensive device than that disclosed in my aforesaid application, which, if desired, may be held in one's hand while the smoke is being emitted therefrom. Thus, in addition to being suitable for carrying in aeroplanes, rubber dinghies, life rafts, life boats and other small vessels, the present smoke signalling device is adapted to be carried by those on exploring expeditions, hikes and the like so that if they become lost they may signal their location.

Whereas, in the device of my said prior application a substantial gas space in the top of the container, above the charge of smoke-producing material, was desirable, due, in part to the large charge of smoke-producing material in the lower portion of the container, and in part to provide a space for the ignition means, the present device carrying a much smaller charge of such material and having space otherwise provided for the ignition means need have substantially less gas space above the charge of smoke-producing material. Hence, the container can be filled to within a short distance of the top. Space for the ignition means is provided in the form of a recess formed in the charge of smoke-producing material and extending downwardly from the top thereof, preferably in the central portion. A simpler and less expensive form of ignition means also is provided.

As the present signalling device is adapted to be held in one's hand while in use, it is provided with holding means in the form of a pair of wire handles pivoted at opposite sides of the container, at the bottom thereof. The handles are of such construction that when the device is not in use they may be folded against the sides of the container with portions thereof extending over the top of the container and frictionally retained in such position. When the device is to be used the handles are swung to positions below the con-

2

tainer where they bracingly engage one another to give firmness.

For a better understanding of the invention reference may be made to the accompanying drawings, in which

Fig. 1 is a front elevation of the device in use,
 Fig. 2 is a vertical sectional view,
 Fig. 3 is a top plan view,
 Fig. 4 is a bottom plan view,
 Fig. 5 is a side elevation,

Fig. 6 is a horizontal sectional view on line 6—6 of Fig. 2, and

Fig. 7 is a partial sectional view showing a modified form of closure for the container.

Referring now to the drawings, the present smoke signalling device comprises a container 1 preferably of metal and generally rectangular in shape. The side walls of the container are crimp-sealed to the top 2 and to the bottom 3 so that outwardly extending flanges are formed. The flanges 4 at the bottom are utilized for a purpose which will appear later.

The side walls and bottom of the container are lined with layers of some relatively non-inflammable, heat-insulating material 5, such as card board, chip board, or the like, which protects the relatively thin metal walls of the container from the heat of the burning charge within.

The container is filled to within a short distance 30 of the top with a charge 6 of smoke-producing material, which for the purpose of this invention may be of any desired composition, but which preferably is one which includes a source of carbon, an oxidizing agent and a substance to impart 25 a desired color to the smoke which is produced, such as the composition of my pending application, Serial No. 514,654, filed December 17, 1943. The charge of smoke-producing material is formed in the container with a longitudinally-extending recess 7 which performs the dual function 40 of providing space for ignition means to be described, and an expansion space for gases which are formed when the charge 6 is ignited. It also provides a space into which any oily or tarry 45 substance formed on the burning top surface of the charge may drain so that it will not interfere with the free burning of the material.

The upper surface of the charge 6 is covered 50 with a sheet 8 of nitrocellulose or other readily inflammable material which assists in igniting the charge when the ignition means is set into operation. A perforated metal cover 9 overlies the inflammable sheet and is held in place by upturned flanges 11 which are of such width as 55 to extend to the top 2 of the container so that

the top presses against them and forces the perforated plate against the inflammable cover sheet 8 to hold it tight against the end of fuses of the ignition means.

The top 2 has an upstanding neck 12 which has an open upper end closed by an expansible closure 13 of well known construction. The expansible side of the closure may be released from engagement with the neck by manipulation of the finger piece 14 in a manner well understood. The closure 13 carries a sealing disc 15 which hermetically seals the container when the closure is in clamping engagement with the neck.

The ignition means for the charge of smoke-producing material includes a tubular fiber member 16 which is held in the position shown in Fig. 2 by being clamped between the perforated cover plate 9 and the bottom of the recess 7. Fuses 17 extend from the bottom of the tubular member 16, upwardly along the sides of the recess 7 and have their free ends overlying the charge of smoke-producing material and between and in contact with it and the inflammable cover sheet 8. The inside of the upper end of the tubular member 16 has a coating 18 of a phosphorus composition or other friction-ignitable material. A friction primer member 19 extends through the upper end of the tubular member 16 and has its lower end 21 coiled and in frictional contact with the coating 18. The other end of the primer member is secured to the eye 22 of a cotter pin 23 which has its free ends 24 soldered or otherwise secured to the inner side of the closure 13.

The neck 12 has an outwardly extending groove 25 in which a metal disc 26 is seated. The opening 27 in the disc is of such size as to restrict to the desired extent the escape of the smoke, so that the smoke will be ejected therethrough in the form of a relatively thin column which will rise to a substantial height in the air.

A layer 28 of some moisture absorbing material, such as silica gel, covers the top of the perforated cover plate 9 and absorbs any moisture which may be in the space above the charge 6; or which might possibly find its way into that space. Thus, the charge of smoke-producing material always is maintained in a dry condition and hence readily ignitable.

A clamping plate 29 has upturned side flanges 31 which slip over the seam flanges 4 at the bottom of the container and securely holds the plate to the container. A metal strap 34 extending between the clamping plate 29 and the bottom of the container has its end portions extending beyond the edges of the container and folded over upon themselves and inserted under the container, between the bottom thereof and the clamping plate. Loops 32 are formed where the strap ends are bent over upon themselves forming bearings for one end of bent wire handles 33 which, when the device is not in use, extend upwardly along the edges of the container. The closed ends 34 of the handles are bent inwardly, over the top of the container. The inwardly-bent portions of the handles extend downwardly slightly, and the length of the handles is such that it is necessary to spring the bent-over portions over the seam flange at the top of the container. Thus they are retained in that position when the device is not in use.

When the device is to be put into use the handles are swung downwardly to the position shown in Fig. 1 and the loops at their free ends caused to interdigitate so that the closed end of one

5 handle bears against the bent-over portion of the other handle to lock them against one another, as shown in Fig. 1. In such position the handles give firmness when the signal is in use. The handles then are firmly gripped in one hand while the closure 13 is released from the neck 12 and quickly pulled to cause the primer coil 21 to move frictionally along the coating 18 of friction-ignitable material and ignite it. The burning of the coating 18, in turn ignites the ends of the fuses 17 within the tubular member 16. As the fuses burn they set fire to the inflammable cover sheet 8 and the charge 6 of smoke-producing material. After the charge is burning well, the device may be swung with a circular motion to cause the smoke being ejected through the opening 27 in the disc 26, and from the open end of the neck 12 to rise in a spiral column.

10 If the device is used at sea and it is desired to have it float on the water while it is burning, it should be ignited, as described above, and after it has been burning for a period of thirty seconds or longer tossed into the sea. Should it be tossed into the sea immediately after being ignited, and before it was burning well, water might enter the neck 12 on the container being submerged when tossed in, and the device thereby drowned. However, if a period of at least thirty seconds elapses between ignition and the tossing of it into the sea, the charge of smoke-producing material will be burning with such vigor that the force of the smoke being ejected through the opening 27 will be sufficient to prevent water passing therethrough into the container. Therefore, even if the device submerges, on initially being tossed into the water it shortly will reappear on the surface ejecting smoke the same as before it submerged.

15 When the device is thrown into water it is caused to float in an upright position due to the weighting effect of the handles extending downwardly from the bottom of the container 1. Referring to Fig. 2, it will be noted that a space is formed between the bottom 3 of the container and the clamping plate 29 and strap 34 which extends the full length of the bottom except for entrance spaces at the corners of the container, at opposite sides of the strap (Fig. 4). This hollow space, with the open spaces at the corners, forms an open bottom stabilizing "skirt" which retards or eliminates rocking and causes the device to remain upright despite the action of current or waves. The four spaces at the corners permit water to wash freely through the space without upsetting the device or diminishing its smoke dispensing function.

20 To protect the container from the elements it is well coated with water-proof paint and then given a coating of a salt-water, spray-proof lacquer. As a precaution against the entry of water or moisture into the container, the neck 12 and the closure 13 may be dipped in water-proof wax.

25 A smoke producing device as above described having a height of 4 1/4 inches, a width of 3 3/4 inches and a thickness of 1 1/8 inches and filled with smoke-producing material of the kind described in my said application Serial No. 514,654 which became Patent Number 2,411,070 on November 12, 1946, will burn for about two minutes and produce about 10,000 cubic feet of smoke, thus producing a column which, under favorable atmospheric conditions, will rise to a height of several hundred feet.

30 In Fig. 7 there is shown a modified form of closure for the neck of the container. As shown

in this figure, the outer end 35 of the neck 12' is threaded to receive a correspondingly threaded closure cap 36. The cap 36 carries a sealing disc 15 like the one shown in Fig. 2 and the free ends of the cotter pin 23 are secured in appropriate manner to the inner side of the cap 36, as in the form previously described.

The invention has been described in connection with a preferred form of the invention. However, it will be understood that various changes may be made within the scope of the appended claims without departing from the spirit of the invention.

I claim:

1. A smoke signaling device comprising a container, a charge of smoke-producing material in the container, said charge of smoke-producing material having a recess therein extending from a surface thereof, a tubular member within said recess, said tubular member having a coating of friction-ignitable material on the inside of a portion thereof, a friction primer coil in contact with said friction-ignitable material, means for moving said friction primer coil while it is in contact with said friction-ignitable material to ignite the latter, a sheet of readily inflammable material over said surface of the charge of smoke-producing material, a perforated metal sheet holding said sheet of readily inflammable material adjacent said surface of smoke-producing material, and fuse means adapted to be ignited by the friction-ignitable material and having portions extending from said tubular member and lying in contact with said surface of the smoke-producing material and between it and the sheet of inflammable material.

2. A smoke signaling device comprising a container having a neck with an opening extending therefrom, a closure removably secured to the neck and closing the opening therein, a charge of smoke-producing material within the container, said charge of smoke-producing material having a recess therein extending from the surface thereof opposite the neck, a sheet of readily inflammable material over said surface of the smoke-producing material, a perforated cover plate fixed relative to the neck and maintaining said sheet of readily inflammable material adjacent said surface of the charge of smoke-producing material, a tubular member within said recess, said tubular member having a portion of the inside thereof coated with friction-ignitable material, a friction primer member, means so connecting the friction primer member with the closure that when the closure is removed from the neck and quickly pulled the friction primer member will be caused to move relative to and in contact with the friction-ignitable material and ignite the same, and fuse means extending from said tubular member and lying in contact with said surface of the charge of smoke-producing material and between it and the readily inflammable sheet.

3. A smoke signaling device comprising a container having a neck with an opening extending therefrom, a closure removably secured to the neck and closing the opening therein, a charge of smoke-producing material within the container, said charge of smoke-producing material having a recess therein extending from the surface thereof opposite the neck, a sheet of readily inflammable material over said surface of the smoke-producing material, a perforated cover plate fixed relative to the neck and maintaining said sheet of readily inflammable material ad-

jacent said surface of the charge of smoke-producing material, a member within said recess, said member having a portion thereof coated with friction-ignitable material, a friction primer, means so connecting the friction primer with the closure that when the closure is removed from the neck and quickly pulled the friction primer will move relative to and in contact with the friction-ignitable material and ignite the same, 5 fuse means positioned adjacent the member having the coating of friction-ignitable material, a portion of said fuse means being in contact with said surface of the charge of smoke-producing material and between it and the readily inflammable sheet, and means in said neck for restricting the free passage of smoke from the container.

4. A smoke signaling device comprising a container having a neck with an opening extending therefrom, a closure removably secured to the neck and closing the opening therein, a charge of smoke-producing material within the container, said charge of smoke-producing material having a recess therein extending from the surface thereof opposite the neck, a sheet of readily inflammable material over said surface of the smoke-producing material, a perforated cover plate fixed relative to the neck and maintaining said sheet of readily inflammable material adjacent said surface of the charge of smoke-producing material, a tubular member within said recess, said tubular member having a portion of the inside thereof coated with friction-ignitable material, a friction primer, means connecting the friction primer with the closure that when the closure is removed from the neck and quickly pulled the friction primer will be caused to move relative to and in contact with the friction-ignitable material and ignite the same, fuse means extending from said tubular member and lying in contact with said surface of the charge of smoke-producing material and between it and the readily inflammable sheet, and a disc extending across the neck having an opening therein affording a restricted passage for the passage of smoke from the container.

5. A smoke signaling device comprising a container having a neck with an opening extending therefrom, a closure removably secured to the neck and closing the opening therein, a charge of smoke-producing material within the container, said charge of smoke-producing material having a recess therein extending from the surface thereof opposite the neck, a sheet of readily inflammable material over said surface of the smoke-producing material, a perforated cover plate fixed relative to the neck and maintaining said sheet of readily inflammable material adjacent said surface of the charge of smoke-producing material, a tubular member within said recess, said tubular member having a portion of the inside thereof coated with friction-ignitable material, primer means including a coil in contact with said friction-ignitable material, means 55 so connecting the primer means with the closure that when the closure is removed from the neck and quickly pulled the primer coil will be caused to move relative and in contact with the friction ignitable material and ignite the same, fuse means extending from said tubular member and lying in contact with said surface of the charge of smoke-producing material and between it and the readily inflammable sheet, the neck having an outwardly extending groove therein, and a disc 60 fixed in said groove and having an opening there-

in affording a restricted passage for smoke from the container.
